UNITED STATES PATENT OFFICE.

WILLIAM B. GERE, OF SYRACUSE, NEW YORK, ASSIGNOR TO THE MERRELL-SOULE COMPANY, OF SAME PLACE.

DESIGN FOR A CARTON OR ENVELOP.

SPECIFICATION forming part of Design No. 28,639, dated May 17, 1898.

Application filed December 15, 1897. Serial No. 662,082. Term of patent 14 years.

To all whom it may concern:

Be it known that I, WILLIAM B. GERE, a citizen of the United States, residing at Syracuse, in the county of Onondaga and State of New York, have invented and produced a new and original Design for a Carton or Envelop, of which the following is a specification, reference being had to the accompanying drawings, making a part thereof.

10 This design relates to the configuration of a carton or envelop of the kind which are used for inclosing the round tin cans containing canned or preserved goods—for instance, vegetables, fruits, fish, meat, and the like.

15 In the accompanying drawings, Figure 1 is a perspective view of a carton or envelop embodying my design. Fig. 2 is a plan view thereof. Fig. 3 is a vertical section in line 3 3, Fig. 2, viewed obliquely.

20 Like letters of reference refer to like parts in the several figures.

The essential feature of my design consists of a hollow eight-sided prismatic body having

at each end a head, which is composed of radially-converging triangular sections. 25

A represents the body of the carton or envelop, having the form of a hollow eight-sided prism.

B represents the heads, which are formed at the upper and lower ends of this hollow 30 body and which are each composed of eight triangular sections c. Each of these triangular sections is united at its base to the end of one of the sides d of the body and extends therefrom inwardly to a common center, at 35 which the apices or points of the triangular sections of the same head meet.

I claim as my invention—

The design for a carton or envelop, substantially as herein shown and described. 40

Witness my hand this 4th day of December, 1897.

WILLIAM B. GERE.
